LIDINGÖN, SWEDEN.

ROTATING FIELD-MAGNET.

1,273,385.

Specification of Letters Patent.

Patented July 23, 1918.

Application filed January 19, 1918. Serial No. 212,772.

To all whom it may concern:

Be it known that we, BIRGER LJUNGSTRÖM, director, and FREDRIK LJUNGSTRÖM, chief engineer, subjects of the King of Sweden, residing at Narvavägen 21, Stockholm, Sweden, and Brevik, Lidingön, Sweden, have invented certain new and useful Improvements in Rotating Field-Magnets, of which the following is a specification.

- 10 The present invention relates to rotating field-magnets and consists chiefly in the slots of the field-magnet being provided with a groove at each side of the bottom, into which the side insulations may enter.
- 15 The invention also comprises other arrangements which will be hereinafter described in connection with some preferred embodiments of the invention.

One object of the invention is to obtain 20 the same creep-length by means of a thin bottom insulation as may be obtained by a thicker one and, further, to increase the sectional area of the rotating field-magnet and thus to increase its capacity.

25 The accompanying drawing illustrates some preferred embodiments of the invention. Figure 1 shows a cross-section through a field-magnet with parallel slots, Fig. 2 part of a cross-section with radial slots, Figs. 30 3 and 4 cross-sections of different slots, Fig. 5 a section of a slot with an ordinary bottom insulating strip, and Figs. 6 and 7 different forms of bottom insulating strips according to the present invention.

35 1 designates the slot which is closed by a longitudinal wedge 2 serving to retain the winding 3. Provided in the bottom of the slot are grooves 4 (Figs. 1, 2, 3) into which the ends of the side insulations 5 enter. 40 Preferably said grooves are given a round cross-section to prevent cracks in adjacent parts. Due to the fact that the side insulations 5 enter into these grooves 4, the insulating plates 6 may be made relatively thin, as 45 the electrical creep-length from the conductors in the slot to the iron close to the inner insulation of the slot is determined by the cross-sectional measures of the groove 4.

By the arrangement described the same 50 creep-length is obtained by means of the thin bottom insulation 6 (Fig. 3) as by the ordinary, thick insulation shown in Fig. 5. The grooves may then be made correspondingly shallower whereby the cross-section of 55 the rotating field-magnet will be larger.

Due to this fact the area available for the magnet flux, and thus also the capacity of the rotating magnet, will be increased. As a consequence the total capacity of the electrical generator is also increased.

As shown in Figs. 4 and 7 the grooves may be made in a separate strip placed on the bottom of the slot and preferably consisting of iron. If a similar strip 8 is used beneath the wedge 2 (Fig. 4), the same advantage is obtained in respect of great creep-length and thin and flexible insulation. A thin and flexible insulation is particularly wanted with regard to the fact that the conductors 3 are forced together by the wedge 60 being driven into the slot. Further a relatively thick strip 8 is wanted to prevent damage of said insulation by the insertion of the wedge.

In certain cases a variation of the magnetic flux is wanted which may be effected by making one of the strips 7 and 8, Fig. 4, or both of magnetic or non-magnetic material whereby a certain adjustment of the potential and magnetization curve may be 75 obtained without any other alteration.

Figs. 6 and 7 show some modifications of the strips 7 and 8 shown in Fig. 4 the strips being composed of magnetic material 9 and of non-magnetic material 10.

Claims.

1. A rotating field-magnet provided with slots for containing conductors and insulating linings for such slots, each slot having grooves at its sides under the bottom part 90 of the insulating lining, said grooves being arranged to allow the side walls of the insulating lining to enter them for the purposes set forth.

2. A rotating field-magnet provided with 95 slots for containing conductors, and insulating linings for such slots, each slot having grooves at its sides under the bottom part of the insulating lining, said grooves being arranged to allow the side walls of the insulating lining to enter them and formed in a separate strip located in the bottom of the slot.

3. A rotating field-magnet provided with 105 slots for containing conductors and with insulating linings for said slots, each slot having grooves at its sides under the bottom part of the insulating lining and being closed by a wedge, the said grooves being formed in a separate strip located in the 110

bottom part of the slot and a similar strip similarly grooved being located under the wedge, the grooves of said strips being arranged to allow the side walls of the insulating lining to enter them for the purposes set forth.

4. A rotating field-magnet provided with slots for containing conductors, insulating linings for said slots, each slot having 10 grooves at its sides adapted to receive the side walls of said insulating linings and separate strips at the bottom and top of said

slots in which strips said grooves are formed, at least one of said strips being partly of magnetic and partly of non-magnetic ma- 15 terial.

In testimony whereof we affix our signatures in presence of two witnesses

BIRGER LJUNGSTRÖM.

FREDRIK LJUNGSTRÖM.
